Primary Examiner — Michelle E. Wilson*Assistant Examiner* — Caitlin A Laverty(74) *Attorney, Agent, or Firm* — Murray, Ziel & Johnston; Aaron Powell(57) **CLAIM**

The ornamental design for a knitting needle, as shown and described.

DESCRIPTION

FIG. 1 is a top, front, right side perspective view of a knitting needle, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the knitting needle in detached state.

The evenly dashed broken lines illustrate portions of the knitting needle and form no part of the claimed design.

1 Claim, 8 Drawing Sheets(56)
